(57) **ABSTRACT**

The drilling rig includes a first substructure and a second substructure. The second substructure is positioned generally parallel to and spaced apart from the first substructure and generally the same height as the first substructure. The drilling rig further includes a drill rig floor coupled to the first and second substructures, where the drill rig floor positioned substantially at the top of the first and second substructures.

CROSS-REFERENCE TO RELATED
APPLICATIONS

This application is a continuation of U.S. non-provisional application Ser. No. 15/191,094, filed Jun. 23, 2016, which is a continuation of U.S. non-provisional application Ser. No. 14/180,049, filed Feb. 13, 2014, and now granted as U.S. Pat. No. 9,810,027, which is itself a non-provisional application which claims priority from U.S. provisional application No. 61/764,259 filed Feb. 13, 2013.

FIELD OF THE DISCLOSURE

The present disclosure relates generally to drilling rigs, and specifically to box-on-box rig structures for land drilling in the petroleum exploration and production industry.

BACKGROUND OF THE DISCLOSURE

Land-based drilling rigs may be configured to be skidded from location to location to drill multiple wells within the same area known as a wellsite. In certain situations, it is necessary to skid across an already drilled well for which there is a well-head in place. Further, mast placement on land-drilling rigs may have an effect on drilling activity. For example, depending on mast placement on the drilling rig, an existing well-head may interfere with the location of land-situated equipment such as, for instance, existing well-heads, and may also interfere with raising and lowering of equipment needed for operations.

SUMMARY

The present disclosure provides for a drilling rig. The drilling rig may include a first substructure; a second substructure, the second substructure being positioned generally parallel to and spaced apart from the first substructure and being generally the same height as the first substructure; and a drill floor coupled to the first and second substructures, the drill floor positioned substantially at the top of the first and second substructures.

The present disclosure also provides for a substructure for use in a drilling rig. The substructure may include a substructure frame, the substructure frame configured to at least partially support a drilling floor; and a tank support structure affixed to the substructure.

The present disclosure also provides for a drilling rig. The drilling rig may include a first substructure; a second substructure, the second substructure being positioned generally parallel to and spaced apart from the first substructure and being generally the same height as the first substructure; and a drill floor coupled to the first and second substructures. The drill floor may be positioned substantially at the top of the first and second substructures. The drill floor may include a V-door, the V-door generally aligned with a side of the drill floor, and the side of the drill floor with which the V-door is aligned may face towards the first or second substructure. The drilling rig may also include a mast coupled to the drill floor. The drilling rig may also include a tank support structure affixed to the first or second substructure. The tank support structure may include a tank and mud process equipment. The drilling rig may also include a grasshopper positioned to carry cabling and lines to the drilling rig. The grasshopper may be positioned to couple to the drill floor

generally at a side of the drill floor, and the side of the drill floor to which the grasshopper couples may face towards the first or second substructure.

5 BRIEF DESCRIPTION OF THE DRAWINGS

The summary and the detailed description are further understood when read in conjunction with the appended drawings. For the purpose of illustrating the present disclosure, there are shown in the drawings exemplary embodiments of said disclosure; however, the disclosure is not limited to the specific methods, compositions, and devices disclosed. In addition, the drawings are not necessarily drawn to scale. In the drawings:

15 FIG. 1 is a side elevation from the driller's side of a drilling rig consistent with at least one embodiment of the present disclosure.

FIG. 2 is an overhead view of a drilling rig consistent with at least one embodiment of the present disclosure.

20 FIG. 3 is an isometric view of a drilling rig consistent with at least one embodiment of the present disclosure.

FIG. 4 is an isometric view of a drilling rig consistent with at least one embodiment of the present disclosure.

25 DETAILED DESCRIPTION

The present disclosure may be understood more readily by reference to the following detailed description, taken in connection with the accompanying figures, which form a part of this disclosure. It is to be understood that this disclosure is not limited to the specific devices, methods, applications, conditions or parameters described and/or shown herein, and that the terminology used herein is for the purpose of describing particular embodiments by way of example only and is not intended to be limiting of the present disclosure. Also, as used in the specification, including the appended claims, the singular forms "a," "an," and "the" include the plural, and reference to a particular numerical value includes at least that particular value, unless 30 the context clearly dictates otherwise. The term "plurality," as used herein, means more than one.

35 FIG. 1 depicts a side elevation of drilling rig 10 from the "driller's side" consistent with at least one embodiment of the present disclosure. Drilling rig 10 may include drill rig floor 20, right substructure 30, and left substructure 40. Right and left substructures 30, 40 may support drill rig floor 20. Mast 50 may be coupled to drill rig floor 20. As would be understood by one having ordinary skill in the art with the benefit of this disclosure, the terms "right" and "left" as used 40 herein are used only to refer to each separate substructure to simplify discussion, and are not intended to limit this disclosure in any way. Mud gas separator tank 60 may be positioned within right or left substructures 30, 40, as shown in FIG. 1 or cantilevered from the left or right substructures 30, 40 as shown in FIGS. 3 and 4. V-door side 22 of drilling rig 10 may be located over right substructure 30. The V-door side 52 of mast 50 may correspondingly face right substructure 30. Pipe handler 24 may be positioned to carry piping through a V-door as understood in the art positioned on 45 V-door side 22 of drilling rig 10. In some embodiments, grasshopper 26 may be positioned to carry cabling and lines to drilling rig 10. In other embodiments (not shown), V-door side 22 and mast V-door side 52 may face left substructure 40. In some embodiments, as depicted in FIG. 1, blow out 50 preventer 90 may be located between left substructure 40 and right substructure 30, i.e. drilling rig 10 may be centered over a wellbore.

In some embodiments, tank support structure **80** and tanks **70** may be included in drilling rig **10**. Tank support structure **80** may be affixed to right substructure **30** or left substructure **40** by means known to those of ordinary skill in the art with the benefit of this disclosure, including, but not limited to, welding and bolting. As shown in FIG. 1, tank support structure **80** may be affixed to left substructure **40**. Tank support structure **80** may be located on the opposite substructure from V-door side **22** of drilling rig **10**. Tanks **70** may, for example, be mud tanks, auxiliary mud tanks, or other tanks useful in drilling operations and may be located within tank support structure **80**. In some embodiments, mud process equipment **100** may also be mounted within tank support structure **80**. Mud process equipment may include, for example, shakers, filters, and other equipment associated with the use of drilling mud.

FIG. 2 depicts an overhead view of drilling rig **10** consistent with at least one embodiment of the present disclosure in which V-door side **22** of drilling rig **10**, drill rig floor **20**, and tank support structure **80** are shown. In some embodiments, choke manifold **102** may likewise be located on the rig floor. In some embodiments, accumulator **104** may likewise be located on the rig floor.

FIG. 3 depicts drilling rig **10** having drill rig floor **20**. Drill rig floor **20** includes V-door side **22**. Pipe handler **24** may connect to drilling floor **20** through V-door **28**. FIG. 3 further depicts V-door side **22** of drilling rig **10** above right substructure **30** and perpendicular to the long axis of right substructure **30**. FIG. 3 also depicts V-door side **52** of mast **50** perpendicular to the long axis of right substructure **30**. Left substructure **40** is shown opposite right substructure **30**. As shown in FIG. 3, right substructure **30** and left substructure **40** are elongated substructures. FIG. 4 depicts tank support structure **80** affixed to left substructure **40**. Tanks **70** are shown positioned within tank support structure **80**. Mud process equipment **100** is located within tank support structure **80**.

As they are mounted directly to a substructure (**30** or **40**) of drilling rig **10**, tanks **70**, mud process equipment **100**, choke manifold **102**, and accumulator **104** may travel with drilling rig **10** during a skidding operation. As such any pipe or tubing connections between or taken from tanks **70**, mud process equipment **100**, choke manifold **102**, and/or accumulator **104** may remain connected during the skidding operations. This arrangement may allow, for example, more rapid rig disassembly ("rigging-down") and assembly (or "rigging-up") of drilling rig **10** before and after a skidding operation.

Additionally, by facing V-door side **22** of drilling rig **10** toward one of the substructures **30**, **40**, equipment and structures that pass through the V-door or to drilling floor **20** from V-door side **22** of drilling rig **10** may, for example, be less likely to interfere with additional wells in the well field.

One having ordinary skill in the art with the benefit of this disclosure will understand that the specific configuration depicted in FIGS. 1, 2 may be varied without deviating from the scope of this disclosure.

Those skilled in the art will appreciate that numerous changes and modifications can be made to the preferred embodiments of the present disclosure and that such changes and modifications can be made without departing from the spirit of said disclosure. It is, therefore, intended that the appended claims cover all such equivalent variations as fall within the true spirit and scope of said disclosure.

What is claimed is:

1. A box-on-box land based drilling rig comprising:
a first elongated substructure;

a second elongated substructure, the second elongated substructure being positioned generally parallel to and spaced apart from the first elongated substructure;
a drill rig floor fixedly coupled to the first and second elongated substructures; and

a mast coupled to the drill rig floor, wherein the mast further comprises a V-door side and wherein the V-door side of the mast is perpendicular to a long axis of the first elongated substructure,

wherein the box-on-box land based drilling rig is adapted to be traveled in an assembled state through a wellsite.

2. The land based drilling rig of claim 1, further comprising a choke manifold, the choke manifold positioned on the drill rig floor.

3. The land based drilling rig of claim 2, wherein a catwalk is coupled to the first elongated substructure or second elongated substructure and is adapted to travel with the land based drilling rig.

4. The land based drilling rig of claim 1, wherein the land based drilling rig is a box-on-box rig.

5. The land based drilling rig of claim 1, wherein the drill rig floor comprises a V-door, the V-door generally aligned with a V-door side of the drill rig floor, the V-door side of the drill rig floor aligned perpendicular to a long axis of the first elongated substructure.

6. The land based drilling rig of claim 1 further comprising one or more tanks, the one or more tanks positioned within the land based drilling rig.

7. The land based drilling rig of claim 1 further comprising a mud gas separator, the mud gas separator positioned within the first elongated substructure or the second elongated substructure.

8. The land based drilling rig of claim 1 further comprising a pipe handler, the pipe handler positioned to carry piping through a V-door on the V-door side of the drill rig floor.
